UNITED STATES PATENT OFFICE.

BENJAMIN H. DIETZ AND ALBERT E. HANSEN, OF CHICAGO, ILLINOIS.

DESIGN FOR A COMBINED PHONOGRAPH AND RADIO RECEIVER CABINET.

Application filed February 23, 1924. Serial No. 8,719. Term of patent 14 years.

● *To all whom it may concern:*

Be it known that we, BENJAMIN H. DIETZ and ALBERT E. HANSEN, citizens of the United States, residing at Chicago, in the county of Cook and State of Illinois, have invented a new, original, and ornamental Design for a Combined Phonograph and Radio Receiver Cabinet, of which the following is a specification, reference being had to the accompanying drawing, forming a part thereof.

The drawing represents a view in per-

spective of our new design for a combined phonograph and radio receiver cabinet.

We claim:

The ornamental design for a combined phonograph and radio receiver cabinet, as shown.

BENJAMIN H. DIETZ.
ALBERT E. HANSEN.
